UNITED STATES PATENT OFFICE

FREDERICK E. VAN SLYKE, OF COLUMBUS, OHIO, ASSIGNOR TO THE JEFFREY MANUFACTURING COMPANY, OF COLUMBUS, OHIO, A CORPORATION OF OHIO

MINING APPARATUS

Application filed October 26, 1921. Serial No. 510,459.

The present invention relates to certain new and useful improvements in mining apparatus, and has for its especial object a longitudinally expandible post, adapted to forcibly engage the floor and roof of a mine chamber to support material dislodging devices in operative relation to the material to be mined, to afford an abutment against which said dislodging devices may react, or to support the mine roof for the protection of such dislodging devices and of the working conditions adjacent the face of the vein.

A further object is to provide a post of the class described associated with power actuated means for its bodily movement relative to the material to be mined and for its adjustment in operative position.

A further object is to provide a system of devices of the class described adapted to follow the recession of the working face for the protection of the material dislodging devices and the maintenance of working conditions during the operation of the mine.

These and other objects will be fully set forth in the following specifications reference being had to the accompanying drawings of which

Fig. 1 is a side elevation of the primary unit of my system of mine posts, arranged to position and support the coal dislodging devices.

Fig. 2 is a plan view of the devices illustrated in Fig. 1.

Fig. 3 is a rear elevation of the devices illustrated in Figs. 1 and 2.

Fig. 4 is a sectional view taken along the line IV—IV of Fig. 2.

Fig. 5 is a sectional view of the hydraulic pump by which certain of the parts are actuated.

Fig. 6 is a sectional view of the devices by which the hydraulic devices are controlled.

Fig. 7 is a side elevation of the secondary unit of my system of mine posts, adapted to the support of the mine roof.

Fig. 8 is a plan view of the devices illustrated in Fig. 7.

Figs. 9 and 10 are details of the propelling mechanism by which my improved mine posts may be bodily moved over the floor

of the mine from one operative position to another.

Fig. 11 is a diagrammatic plan view of a mine chamber illustrating the method of operating the devices of this invention.

Like numerals refer to similar parts in the several figures.

In the drawings the numeral 1 refers to a substantially perpendicular cylinder to the bottom of which is attached a broadly expanded base plate 2 adapted to engage the floor of the mine and to afford a broad bearing thereon. Fitting in the cylinder 1 is a plunger 3 adapted to be moved upwardly when the water is forced into the lower portion of the cylinder, and to fall by its own weight as the water is withdrawn therefrom. A suitable gland 4 having an elastic packing 5 is provided to confine the water in the cylinder 1, in the manner well understood by persons skilled in the hydraulic art. Screw threaded to the upper portion of the plunger 3 is an extension 6 having a laterally expanded head 7 adapted to engage the roof of the mine and to afford a broad bearing therewith. By the adjustment of the extension 6 relative to the plunger 3 the device may be adapted to use in mines having a wide range of vertical dimensions. Water may be admitted to the cylinder 1 for the actuation of the plunger 3 through the tube 8 in a manner to be more fully hereinafter set forth.

Attached to the base plate 2 are upstanding pedestal brackets 9 having guide ways 85 wherein the axle journal boxes 10 are vertically slideable. Journaled in the boxes 10 are the axles 11 and 12 to which are attached the ground engaging wheels 13. Compression springs 14, positioned within the pedestal brackets 9 and bearing upon the tops of the journal boxes 10, transfer the weight of the base plate 2, and the parts mounted thereon, to the wheels 13. When the plunger 3 is forced upwardly, to cause the head 7 to contact with the roof of the mine, the springs 14 will be compressed to permit the base plate 2 to contact with the mine floor, thereby relieving the wheels and axles of the excessive strain caused by the pressure upon the post when in operative position. When the

plunger 3 is again withdrawn into the cylinder 1, the springs 14 will automatically lift the bed plate 2 clear of the floor to allow free movement of the machine from one operative 5 position to another.

Means to rotate the wheels 13, to move the machine over the mine floor, is provided in the cylinder 15 which is pivotally supported upon the axle 12 by the lugs 16. Reciprocable 10 in the cylinder 15 is a plunger 17 adapted to be moved outwardly by the pressure of the water on the piston head 18, and to be moved inwardly by the pressure of the spring 19 upon the piston. Water for the actuation of 15 the plunger 17 may be admitted to and withdrawn from the cylinder 15 through the tube 20 as will be more fully described. Formed on the projecting end of the plunger 17 is a rack 21 arranged to engage with the spur pinion 22 which is rotatable on the axle 11. The rack 21 is held in contact with the pinion 22 by a roller 23 carried by the yoke 24 which is rotatable about the axle 11, and when the rack is moved in either direction the pinion 20 25 will be rotated thereby. The pinion 22 is formed integral with the driving member 25 of a roller ratchet clutch of well known design, the driven member 26 of which is keyed to the axle 11. A plurality of rollers 27, interposed between the opposing faces of the clutch members 25 and 26 serve to operatively connect these members together to drive the axle 11 when the plunger 17 moves outwardly, and releases such connection to permit the 30 35 free rotation of the pinion 22 as the plunger 17 moves in the reverse direction.

The construction above described is adapted to position and support any preferred type of mining apparatus, and afford a stable 40 abutment against which such apparatus may react. For the purposes of illustration I have shown, in Figs. 1, 2 and 3 of the drawings, a mining apparatus comprising a cylinder 28 fitted with a longitudinally reciprocable plunger 29 to the projecting end of which is attached a wedge 30 adapted to be forced into the body of the vein to split off fragments therefrom. The customary packing gland 31 with its elastic packing 32, is provided to prevent 45 50 the escape of water along the sides of the plunger, and said plunger is provided with a piston head 33 adapted to be acted upon by the water in either end of the cylinder to move the plunger in either direction. Water may 55 be supplied to either end of the cylinder 28 through the tubes 34 and 35 which are connected with the source of supply as will hereinafter appear.

Projecting laterally from the cylinder 1 is 60 a stud 36 which extends through an aperture in the flange 37 formed on the cylinder 28, to pivotally support the coal splitting ram for rotary adjustment in a vertical plane. A nut 38 screw threaded to the stud 36, serves 65 to retain the parts in operative relation.

Formed on the flange 37, concentric with the stud 36, is a segmental gear 39 which is engaged by a worm 40 attached to the worm shaft 41 journaled in the bearings 42 of the base plate 2. The shaft 41 is provided with a hand wheel 43 whereby the worm 40 may be revolved to cause the rotation of the segmental 70 75 80 85 90 95 100 105 110 115 120 125 130 gear 39 about the stud 36 to rotatively adjust the coal dislodging ram. As the worm 40 is of the non-overhauling type the ram will be securely locked thereby in the desired position of angular adjustment.

To provide water connections of sufficient flexibility to permit the angular adjustment of the cylinder 28 the tubes 34 and 35 are provided with the flexible joints comprising two pairs of discs 44, 45 and 46, 47 which are rotatably mounted upon the stud 36 and are held in forced contact by the nuts 48 and 49 respectively. The discs 44 and 46 are attached respectively to the tubes 34 and 35 connected to the cylinder 28, and the discs 45 and 47 are attached to the ends of the tubes 50 and 51 which extend to the source of water supply. On the abutting surfaces of the discs are formed annular grooves 52 which register with the corresponding grooves of the companion discs, and these grooves are connected through passages formed in the bodies of the discs, with the tubes connected with their respective discs, thereby maintaining operative connection between the tubes 34 and 50 and 35 and 51 in all positions of angular adjustment.

Attached to the base plate 2 is a motor 53 which may be of any preferred type suitable to the conditions under which the machine is to be operated. For the purpose of illustration I have shown an electric motor adapted to receive its actuating current from any convenient source of electric supply through a suitable flexible conductor cable 53^a in the manner common in mining practice. A suitable controller 54 is arranged to control the flow of electricity through the motor. Attached to the armature shaft of the motor is a pinion 55 which meshes with a spur gear 56 attached to the countershaft 57. The shaft 57 is journaled in bearings 58 formed on the casing of the motor 53.

Mounted upon the base plate 2 is a pump 59, the plunger 60 of which is connected by the connecting rod 61 with the eccentric 62 attached to the countershaft 57. Valves 63 and 64 are provided for the control of the flow 120 of water through the pump, the suction valve 63 being connected with the supply tank 65 through the tube 66, and the discharge valve 64 with the controller manifold 67 by the tube 68.

The controller manifold 67 consists of a body having two parallel longitudinally extending passages 69 and 70. The supply passage 69 is connected with the tube 68 extending from the pump, and the discharge pas-

sage 70 is connected by the tube 71 with the supply tank 65. A by-pass which includes the back pressure valve 72 connects the passages 69 and 70 together and affords a safe circuit 5 for the water around the pump when there is no outlet for it into any of the hydraulic devices of the machine. Valves 73, 74, 75, 76 and 77 are connected with the manifold 67 by means of suitable fittings, and these valves 10 are connected with the various hydraulic devices of the machine to control the admission of water thereto or the release of water therefrom. As these valves are alike a description of one will apply to all.

Attached to a supporting base 78 is a cylinder 79 in which is longitudinally movable a plunger 80 of such dimensions that it completely fills the cylinder. Formed in the plunger 80 is a circumferential groove 81 15 adapted, when the plunger 80 is in its extreme uppermost position to register with the port 82 which communicates with the supply passage 69 of the manifold, and when the plunger is in its extreme lowermost position 20 to register with the port 83 which communicates with the discharge passage 70 of the manifold. Formed in the wall of the cylinder 79 is a passage 84 adapted to register with the groove 81 when the plunger is in either of 25 its extreme upper or lower positions, and this passage is connected with one of the tubes which leads to the various hydraulic devices 30 of the machine.

The valves 74 and 75 are connected by the tubes 50 and 51 with the cylinder 28. These valves are arranged at opposite sides of the manifold 67, and are provided with a common operative lever 85 so arranged that when the plunger of the valve 74 is moved 35 upward, to admit water to the rear end of the cylinder 28, the plunger of the valve 75 will be moved downward to allow the escape of water from the forward end of the cylinder. 40 By alternate upward and downward movement of the lever 85 the plungers of the valves 74 and 75 may be oppositely moved to cause the plunger 29 to be thrust outwardly against the coal to break off fragments therefrom, or to cause the said plunger to be withdrawn into 45 the cylinder to permit its adjustment preparatory to another thrust.

The valve 73 is connected with the tube 20 which extends to the axle driving cylinder 15, the valve 76 is connected with the tube 8 of the vertical cylinder 1 and the valve 77 is connected with a tube 86 to the end of which is fitted a quick acting hose coupling 87 for a purpose which will hereinafter appear. 55 These valves are provided with operating handles all of which are disposed convenient to the hand of the operator. By the manipulation of these valves water may be admitted to the respective cylinders, confined in said cylinder or permitted to return therefrom to

the supply tank to thereby actuate the devices as above described.

In Figs. 7 and 8 is shown one of the secondary units of my improved mine posts, which is reduced to its simplest form and is 70 adapted to support the mine roof for the protection of the working conditions in the immediate proximity with the working face. As here shown the tubes 8^a and 20^a through which water is supplied to the cylinders 1^a and 15^a, 75 are provided with quick acting hose couplings 88 adapted to engage similar couplings on a flexible hose pipe 89 one end of which is connected to the tube 86 of the primary unit. By this arrangement either of the cylinders 1^a or 15^a may be connected to the valve 77 on the manifold 67 for the admission and control of water to said cylinders. An auxiliary valve 90 is provided to prevent the escape of water 80 from the cylinder 1^a of the secondary unit 85 when the hose pipe 89 is disconnected therefrom.

In Fig. 11 there is shown a longwall mining operation illustrating the method of operation of the devices of this invention. As 90 here illustrated a longwall conveyor 91, which may be of any preferred type, extends parallel with and closely adjacent to the coal face to receive and remove coal as it is broken down. A primary unit "A," supporting dislodging 95 mechanism such as is above described, is arranged to travel parallel with said conveyor in suitable relation thereto, and a plurality of secondary units "B, C, D, E, F, G," are arranged to travel perpendicularly towards the 100 coal face, and are suitably spaced to support the mine roof.

At each cycle of the operation of the dislodging mechanism the primary unit "A" is advanced to a position in suitable relation 105 with the secondary coal face 92 and is clamped in place by the vertical movement of the plunger 3. After the coal dislodging ram has dislodged all of the coal within its reach, the valve 76 is manipulated to permit 110 the plunger 3 to withdraw into the cylinder 1, and the springs 14 to lift the base plate 2 clear of the mine floor. The plunger 17 is then actuated to cause the rotation of the ground engaging wheels 13 thereby advancing 115 the machine to a new operative position. The plunger 3 is then again, forced upwardly to clamp the machine in place ready for the actuation of the coal dislodging ram.

As the breaking down mechanism proceeds 120 across the mine chamber, the secondary units "B, C, D, E, F, G," etc. will be successively moved towards the coal face a distance corresponding with the increment of advance of the coal face. As the primary unit "A" 125 passes each succeeding secondary unit, as for example the unit "C", the flexible hose 89 will be connected to its tube 8, its auxiliary valve 90 opened, and the valve 77 manipulated to permit the plunger 3 of the second- 130

ary unit "C" to withdraw into its cylinder 1^a. The springs 14 will then lift the bed plate 2 clear of the floor. The hose 89 will then be transferred to the tube 20^a and the valve 77 again manipulated to actuate the plunger 17 to rotate the wheels 13 thereby advancing the secondary unit "C" towards the coal face. After such an advance the hose 89 will be transferred to the tube 8 the valve 77 again manipulated to force the plunger 3 into contact with the mine roof, and the auxiliary valve 90 closed to prevent the escape of water from the cylinder 1. After the unit "C" has been securely adapted in its new position the hose 89 may be disconnected to become available for the movement of succeeding secondary units.

What I claim is:

1. In an apparatus of the class described, 20 the combination with a wheeled truck adapted to travel over the floor of the mine, a vertically disposed post carried by said truck and adapted to contact with the mine floor, a roof engaging extension connected with said post, means to move said extension relative to the post to exert pressure upon the mine roof, automatically acting means associated with the truck tending to lift said post from the mine floor as the pressure upon the roof 30 is reduced, and means to propel said truck over the floor of the mine.

2. In an apparatus of the class described, 35 the combination with a wheeled truck adapted to travel over the floor of the mine, a vertically disposed post carried by said truck and adapted to contact with the mine floor, a roof engaging extension connected with said post, means to move said extension relative to said post to exert pressure upon the mine roof, automatically acting means associated with the truck tending to lift said post from the mine floor as the pressure upon the roof 40 is reduced, means to propel said truck over the mine floor, and power devices upon the truck for the actuation of the extension moving devices and the truck propelling devices.

3. In an apparatus of the class described, 50 the combination with a floor engaging base, a wheeled support therefor adapted to travel over the mine floor, means to propel said support, a vertically extending guide mounted upon said base, a member movable longitudinally of said guide, a roof engaging head 55 adjustably connected to said movable member, means to move said movable member along said guide to press said head against the roof of the mine, and automatically acting means tending to lift said base from the 60 mine floor as the pressure upon the roof is reduced.

4. An apparatus of the class described 65 comprising a plurality of wheels adapted to travel over the mine floor, a base supported upon said wheels and adapted to contact

with the mine floor, a roof engaging member, means to force said base and said member into contact with the floor and roof of the mine respectively, and means adapted to actuate the wheels to bodily move the apparatus. 70

5. An apparatus of the class described comprising a base adapted to rest upon the floor of the mine, wheels connected to said base and adapted to travel over the mine 75 floor, means connected with said wheels and adapted to maintain said base spaced from the mine floor, a roof engaging member, means to cause said base and said member respectively to press against the floor and 80 roof of the mine, and power operable means adapted to actuate the wheels to bodily move the apparatus.

6. An apparatus of the class described comprising a base adapted to rest upon the floor of the mine, wheels connected to said base and adapted to travel over the mine floor, means to maintain said base out of contact with the mine floor, a roof engaging member, power actuated means to cause said base and said member respectively to press against the floor and roof of the mine, and means adapted to actuate the wheels to bodily move the apparatus. 90

7. An apparatus of the class described comprising a base adapted to rest upon the floor of the mine, wheels connected to said base adapted to travel over the mine floor, means arranged to maintain said base spaced from the mine floor, a roof engaging member, hydraulically actuated means to cause said base and said member respectively to press against the floor and roof of the mine, and power operable means adapted to actuate the wheels to bodily move the apparatus. 95

8. In an apparatus of the class described, the combination with a frame, of journal bearings attached to said frame, a pair of parallel axles journaled in said bearings, traction wheels attached to said axles, a cylinder pivotally mounted upon one of said axles, a piston reciprocable in said cylinder, a pinion rotatively mounted upon the other of said axles, a rack attached to said piston and engaging said pinion, means to reciprocate the piston to cause the rotation of said pinion, and means automatically acting in one direction to connect said pinion with said axle to cause the rotation of said traction wheel in that direction. 110

9. In a system of apparatus of the class described, a plurality of independently movable trucks, devices carried by each truck to propel it over the mine floor, devices carried by each truck adapted to exert pressure upon the floor and roof of the mine, and power devices carried by one of said trucks adapted to the actuation of the propulsion devices and the pressure exerting devices of any of said trucks as and for the purpose set forth. 125

10. In a system of apparatus of the class described, a plurality of independently movable trucks having traction wheels adapted to travel over the floor of the mine, devices carried by each truck adapted to cause the rotation of said traction wheels to propel the truck, devices carried by each truck adapted to exert pressure upon the floor and roof of the mine, and power devices carried by one of said trucks adapted to the actuation of the wheel rotating devices and the pressure exerting devices of any of said trucks as and for the purpose set forth.

11. An apparatus of the class described comprising supporting wheels adapted to travel over a mine floor, a base supported by said wheels and adapted to rest upon the floor of the mine, a roof engaging member, power actuated means to cause said base and said member respectively to press against the floor and roof of the mine, means adapted to lift said base out of contact with the mine floor and to maintain the same in lifted position, and means adapted to actuate the wheels to bodily move the apparatus.

12. An apparatus of the class described comprising supporting wheels adapted to travel over a mine floor, a base supported by said wheels and adapted to rest upon the floor of the mine, a roof engaging member, power actuated means to cause said base and said member respectively to press against the floor and roof of the mine, resilient means adapted to lift said base out of contact with the mine floor and to maintain the same in lifted position, and means adapted to actuate the wheels to bodily move the apparatus.

13. A system of apparatus of the class described comprising a plurality of independently movable trucks, devices carried by each truck adapted to exert pressure upon the floor and roof of the mine, power devices carried by one of said trucks adapted to actuate the pressure exerting devices of any of said trucks, and means for connecting said power devices with the pressure exerting devices of any of said trucks.

14. The combination with a mining machine and a plurality of movable roof supports located to the rear of said machine, of means on said machine adapted to be detachably secured to selected ones of said supports for moving said supports toward said machine.

15. The combination of a plurality of roof supports adapted to move over a mine floor, a source of motive force on one of said supports, and means for selectively connecting said source to any of said supports for bodily moving the latter.

16. Apparatus of the class described, comprising a plurality of movable roof supports adapted to rest upon a mine floor, a carriage movable adjacent said supports, power generating means on said carriage, translating

devices on said support adapted to propel the latter, and means for selectively connecting said generating means with said devices.

17. The combination with a mining machine and a plurality of movable roof supports adjacent said machine, of power generating means on said machine, translating devices on said supports adapted to propel the latter, and means for selectively connecting said generating means with said devices.

18. The combination of a plurality of roof supports, power generating means on one of said supports adapted to propel the latter, translating devices on said supports adapted to propel the latter, and means for selectively connecting said generating means with said devices.

19. The combination of a plurality of vertically extensible roof supports, power generating means on one of said supports, power translating means on each of said supports for extending them, and means for selectively connecting said generating means with said translating means.

20. The combination of a plurality of vertically extensible roof supports, hydraulic pressure generating means on one of said supports, an expandible chamber on each of said supports adapted upon expansion to extend the supports, and means for selectively connecting said generating means with the chamber of any support.

21. The combination of a plurality of bodily movable and vertically extensible roof supports, hydraulic pressure generating means on one of said supports, pressure translating devices on each of said supports for bodily moving or extending them, and means for selectively connecting said generating means and translating devices.

In testimony whereof, he has affixed his signature.
